Primary Examiner — Elizabeth A. Albert*(74) Attorney, Agent, or Firm* — Kristina Castellano; Castellano PLLC(57) **CLAIM**

The ornamental design for a vase, as shown and described.

DESCRIPTION

FIG. 1 is a front view of a vase showing my new design; FIG. 2 is a front perspective view from the right thereof; FIG. 3 is a perspective view from the back thereof; FIG. 4 is a back view thereof; FIG. 5 is a view from the left thereof; FIG. 6 is a top perspective view thereof; and, FIG. 7 is a right perspective view thereof. The broken lines in FIGS. 2, 3 and 6 define the bounds of the claimed design and form no part thereof.

1 Claim, 7 Drawing Sheets(56)
